US00D858103S

(12) **United States Design Patent** (10) Patent No.: **US D858,103 S**
(45) Date of Patent: ** Sep. 3, 2019

(54) **TOOL CONTAINER**

(71) Applicant: **BLACK & DECKER INC.**, New Britain, CT (US)

(72) Inventors: **Matthew A. Seibert**, Columbus, OH (US); **Marco Lourenco**, Baltimore, MD (US)

(73) Assignee: **BLACK & DECKER INC.**, New Britain, CT (US)

(**) Term: **15 Years**

(21) Appl. No.: **29/672,208**

(22) Filed: **Dec. 4, 2018**

(51) LOC (12) Cl. **03-01**

(52) U.S. Cl.

USPC **D3/294**; D3/905
